UNITED STATES PATENT OFFICE.

CHARLES A. BLUME AND IRA D. BLUME, OF FARMLAND, INDIANA,
ASSIGNORS TO AUTO FENCE MACHINE COMPANY, OF FARMLAND,
INDIANA, A CORPORATION OF INDIANA.

WIRE-FENCE MACHINE.

No. 850,617.

Specification of Letters Patent.

Patented April 16, 1907.

Application filed August 9, 1906. Serial No. 329,805.

To all whom it may concern:

Be it known that we, CHARLES A. BLUME and IRA D. BLUME, of Farmland, county of Randolph, and State of Indiana, have invented 5 a certain new and useful Wire-Fence Machine; and we do hereby declare that the following is a full, clear, and exact description thereof, reference being had to the accompanying drawings, in which like letters refer to like parts.

The object of this invention is to provide a practical and efficient machine for automatically manufacturing wire fabric, especially a wire-fence fabric having a diamond or similar mesh wherein there are longitudinal strand-wires with which other wires are woven diagonally in two directions.

One feature of the invention consists in the weaving mechanism, wherein the longitudinal wires pass through rotary tubes individually and the tubes carry disk-like means overlapping and coacting for revolving a shuttle about said tubes and means for shifting the shuttle alternately from the disks on one tube to the disks on an adjacent tube. Several features of invention are involved in the construction of this weaving mechanism.

Another feature of the invention consists in the manner of constructing the reel and the means for actuating it intermittently that may be regulated automatically as the reeling proceeds or as the coil of fabric on the reel increases in order that the surface of the reel or coil of fabric may have a rotary movement to a uniform extent, and thus have the coils of the mesh or diagonal wires on the longitudinal wires located at a uniform distance apart.

There are several features of invention involved in the details of the construction for 40 the actuation of the reel.

The foregoing and other features of the invention will be understood from the accompanying drawings and the following description and claims.

In the drawings, Figure 1 is an elevation of the left-hand side of the machine. Fig. 2 shows the reel actuating and controlling mechanism as it appears in Fig. 1, but on an enlarged scale, parts being broken away. Fig. 3 is a plan view of the machine, parts being broken away. Fig. 4 is a vertical section on the line 4-4 of Fig. 3 looking in the direc-

tion indicated by the arrows. Fig. 5 is a plan view of the twister mechanism viewed from the line 5-5 of Fig. 4. Fig. 6 is the same as Fig. 5 with the spool mechanism operated farther. Fig. 7 is a horizontal section on the line 7-7 of Fig. 4. Fig. 8 is a vertical section on the line 8-8 of Fig. 7. Fig. 9 is the same as Fig. 7 with the upper plate and twisters removed. Fig. 10 is a side elevation of one form of an arm of a switch, parts being broken away and parts in section. Fig. 11 is a plan view thereof. Fig. 12 is a side elevation of another form of switch-arm. Fig. 13 is a plan view thereof. Fig. 14 is a section on the line 14-14 of Fig. 5, showing the cam-operating means. Fig. 15 is a front elevation of the means for operating and controlling the reel, parts being broken away. Fig. 16 is a horizontal section on the line 16-16 of Fig. 15, parts being broken away and an altered position being shown by dotted lines. Fig. 17 is a side elevation of a part of the means for operating the reel, parts being broken away. Fig. 18 is the same with the cam added, it being a section on the line 18-18 of Fig. 15. Fig. 19 is a side elevation of a shuttle. Fig. 20 is a central longitudinal section thereof. Fig. 21 is a section on the line 21-21 of Fig. 19. Fig. 22 is the lower right-hand corner of Fig. 20, but on an enlarged scale, showing the spring-bolt depressed, the upper portion of said bolt being shown by dotted lines. Fig. 23 is a front elevation of the shuttles and associate twister mechanism. Fig. 24 is a rear elevation of the reel, parts being broken away. Fig. 25 is a vertical longitudinal section thereof. Fig. 26 is a plan view of the double controlling the mechanism. Fig. 27 is a side elevation of the reel and means actuated by the bundle that is wound on the reel for controlling the operation of the reel-actuating mechanism. Fig. 28 is a section on the line 28-28 of Fig. 24. Fig. 29 is a section on the line 29-29 of Fig. 25. Fig. 30 is a central vertical longitudinal section through the twister mechanism shown in Fig. 7. Fig. 31 is a perspective view of the upper and lower twister-heads, parts being broken away. Fig. 32 is a perspective view of the lower twister-head from a position different from that shown in Fig. 31. Fig. 33 is a plan view of the driving-mechanism for the weav-

ing mechanism, parts being broken away. Fig. 34 is a vertical section on the line 34-34 of Fig. 4. Fig. 35 is an elevation of the right-hand side of the spools for holding the wire 5 for the longitudinal strands of the fence and the means for supporting said spools, parts being broken away. Fig. 36 is a bottom view of the worm and screw shown in the lower part of Fig. 2.

10 Referring now to the details of the construction of the machine herein shown for the purpose of illustrating the general nature of our invention, the frame of the machine consists of transverse beams 40, 41, 42, 43, and 15 44, as seen in Fig. 1, with a longitudinal beam 45 at each side of the machine mounted upon said cross-beams. At each side of the machine there are four posts 46, 47, 48, and 49, mounted upon the longitudinal beam 45, and 20 upon said posts there is a longitudinally-extending beam 50 at each side of the machine. There is a cross-plate 51 (shown in Fig. 4) secured at each end to the posts 46 and 47 at each side of the machine, and a cross-beam 25 53, that is mortised at each end into the beams 50. There is an upper frame built upon the lower frame that consists of the vertical posts 54 and a brace 55 and an intermediate brace 56 at each side of the machine 30 and mounted upon the beam 50. This upper frame is strengthened by a cross-plate 57, secured upon brackets 58, that are fastened to the front faces of the vertical posts 54. There is also a rod 59, that extends from one 35 post 54 to the other, as seen in Fig. 4, and forms a part of and strengthens the framework.

At the front portion of the machine two spool-shafts 60 and 61 are mounted in inclined posts 62, that are secured upon the upper part of the front end of the longitudinal beam 45, and said posts 62 are braced by braces 63. The posts 62 at the right-hand side of the machine are provided with slots 40 64, in which the right-hand ends of the shafts 60 and 61 drop and operate. (See Fig. 35.) This enables said free ends of the shafts 60 and 61 to be elevated for the insertion of or removal of spools 65, upon which wire 66 is 45 wound for the strand-wires of the fabric.

As herein shown, there are six spools on the lower shaft 61 and five spools on the upper shaft 60, and one wire leads from each spool, so that a fence fabric will be made having eleven horizontal strands. Any number of spools may be employed so as to provide the desired number of horizontal strands of wire in a fence. The wires 66 from said spools extend around each of the rolls 67 and 68, that are mounted in suitable bearings secured upon the longitudinal beams 45, and thence said wires pass under a roller 69, similarly mounted somewhat to the rear of the front rollers 67 and 68. Thence the wires pass 55 upward through the weaving mechanism and

over another roller 70, mounted at the upper end of the posts 54, and over said roller to a reel 71, that is mounted at the rear of the machine, as will hereafter be explained. These longitudinal strand-wires are first drawn through the machine, as above described, and secured to the reel and made taut before the weaving of the fabric begins. After the weaving of the fabric has commenced the fabric passes from the weaving 75 mechanism up over the roller 70 to the reel, and after said fabric reaches the reel the preceding ends of the strand-wires are cut away and removed. The reel mechanism therefore draws the fence fabric and the strand-wires through the machine and holds the same taut.

Power is applied to the machine through the pulley 75, that is mounted loosely on the shaft 76, which extends transversely through 85 the machine, as appears in Fig. 3. At one end said shaft extends to the left beyond the side of the machine, and its extreme end is mounted in a bearing 77 on a bracket 78, that is secured to the posts 46 and 48, as seen 90 in Fig. 1. There is a friction-clutch 79 secured to the shaft, that is moved into clutching engagement with the pulley 75 by a lever 80, that is fulcrumed at 81 on the bracket 78, said lever being fastened to the downturned 95 end of a rod 83, extending across the machine and mounted in suitable bearings upon the top beam 50, so that said rod may be shifted longitudinally of itself or transversely of the machine by hand-levers 84, one being at each 100 side of the machine and mounted in brackets 85 on the posts 46 and top beams 50. Said levers 84 are connected with said rod by the couplings 86, so that when said hand-levers are moved laterally of the machine they will 105 shift the rod 83 and throw the machine into and out of gear with the pulley 75.

On the shaft 76 there are some bevel-gears 90 secured, that mesh with companion bevel-gears 91, which are secured on short shafts 110 92, that are mounted in bearings 93, fastened upon the plate 53. There are three sets of these short shafts 92, and they extend longitudinally of the machine and are distributed throughout the machine for driving the 115 weaving and twisting mechanism. Upon the front ends of the short shafts 92 there are secured bevel-gears 94, which mesh with companion bevel-gears 95, secured on the lower end of vertical tubes 96. These tubes are mounted at their lower ends upon the plate 51 and serve as guides for the strand-wires and as means for actuating the twisters. Power is transmitted from one tube to another by the gear-wheels 97, 98, and 99. 120 There are three sets or series of tubes 96 and gears. As shown in Figs. 3 and 4, one series or set of four spur-gears 97 at the left are four inches in diameter. The five gear-wheels 98 midway are five inches in diam- 125 99.

eter, and the gear-wheels 99 at the right hand are six inches in diameter. These gear-wheels vary in diameter in order to vary the distance between the strand-wires. Thus it is seen that the first three spaces between the wires at the left are four inches wide, and the next four spaces are five inches wide, and the next three are six inches wide. Two of the tubes, those between the series of different gears, have secured upon them two gears corresponding in size with the gears of the two adjacent series. This is for the purpose of causing absolute uniformity of rotation of the various tubes to avoid the danger of lost motion.

As shown in Fig. 23, there is secured upon each tube, near its lower end, a twister-head 100, which, as appears in Fig. 8, consist of a central hub portion with two radiating disks 101 and 102 near each end of said hub. Said disks are identical in form and arrangement and appear in plan, as shown in Fig. 7; but the twister-heads on the adjacent tubes are inverted with relation to each other, as shown in Fig. 7 and Figs. 23 and 30. Each disk has a pair of oppositely-extending teeth 103, with indentations on each side of said teeth to form the same, as shown at the left-hand end of Fig. 31 and in Fig. 32, so that each twister-head has two disks and four of the teeth 103, the disks and teeth of each twister-head being in vertical alinement with each other. Therefore, as shown in Fig. 30, the adjacent disks of the various twister-heads overlap each other, and the teeth 103 thereof co-operate with each other to move and actuate a shuttle 110.

The upper twister-heads 105 likewise have two disks 106 and 107, all integral with the twister-head and forming a part thereof. These disks 106 and 107 are in vertical alinement. The form of the upper disk 107 is shown in Fig. 5, it being circular in form, except on the two opposite sides it has indentations at 108 to receive the ends of the shuttle. The lower disk 106 of the upper twister-heads is differently formed, as shown in Fig. 31, it having a tooth 109, like the teeth 103 on the lower twister-head, the disk being cut away on each side of said tooth 109, so that an indentation will be formed immediately below and in alinement with the indentation 108 in the disk above.

As the twister-heads revolve they carry around the tube 96, the shuttle 110, (shown in Figs. 19 and 20,) it being in the form of a longitudinal bar, the body portion of which is triangular in cross-section and the upper and lower ends round. Between the ends and body portion there are disk-like plates 111, that ride upon the disks 101 of the lower twister and under the disks 106 of the upper twister, as appears in Fig. 23, to serve as a guide during the revolution of the shuttle around the tube 96. The arms 111

have connected with them loops 112 at the lower end and 113 at the upper end, arranged so that the teeth 103 on the disks of the lower twister-head will enter the loop at the lower end of the shuttle and the tooth 109 on the lower disk 106 of the upper twister-head will enter the loop at the upper end of the shuttle, as shown in Fig. 31. The bobbin 114 is a pencil-like rod on which the wire 115 is wound and which is woven diagonally from one longitudinal strand to another to form the diagonal mesh of the fence fabric. The upper end of the bobbin is reduced and fits in a seat or hole 116 in the plate 111 and the loop 113 at the upper end of the shuttle. The bobbin at its lower end has a longitudinal recess 117, that receives a pin 118, carried in the part 119, connected with the lower arm 111 and pressed upward by a spring 120 in a longitudinal chamber in the part 112. This spring forces the pin 118 into engagement with the lower bobbin to hold it in place. A stop-pin 121 is fastened to the pin 118 and extends through a guiding-slot 122 in the part 119, as shown in Figs. 20 and 22. The lower position of the pin 118 is shown in Fig. 22.

The bobbin 114 has a wire hole 125 in it near the upper end, in which one end of the wire is inserted when one begins to wind the wire on the bobbin. After the bobbin is put in place on the shuttle the other or free end of the wire is passed through a tension-loop 126, that extends loosely through a plate 127 and is pressed downward by a spring 128. Thence the wire is passed up through an opening or passage-way 129 in the upper end of the shuttle, as shown in Figs. 19 and 20.

The position of the shuttles and their relation to the twister-heads and tubes 96 are shown in Figs. 23 and 7. In the machine herein shown there are ten shuttles for eleven longitudinal strands and eleven tubes 96. As stated before, the twister-heads overlap each other, as shown in Figs. 5, 6, and 7. Both the upper and lower series of twister-heads operate in circular openings in what may be called a "twister-box," as shown in Figs. 7 and 8. The twister-box consists of the plates 135 and 136, arranged parallel with each other, and they are secured at each end upon the rods 137 and held by shoulders on said rods the desired distance apart and held together by said rods 137, being riveted or headed. They are provided with circular openings 138 for the twister-heads, said openings cutting into each other and varying in diameter to suit twister-heads of varying diameters, as seen in Fig. 7. The ends of the shuttles are held in said circular openings 138 and in the notches or recesses in the plates on the twister-heads, as shown in Figs. 5 and 6.

The twister-heads are rotated continuously by means heretofore explained and in the direction indicated by the arrows in Fig. 5.

The twister-head boxes for both the upper and lower series of twister-heads are formed the same as that shown in Fig. 8, and which has been described. In Fig. 9 there is shown 5 the lower plate 135 of said box with the twister-heads and the upper plate 136 removed. Along each side of the twister-head box, as shown in Figs. 8 and 9, there is a shifting-bar 140, held in place by brackets 10 141, that are secured by a pin 142 as well as through the plates 135 and 136 of the twister-box. The ends of the shifting-bars, as seen in Fig. 7, are pivoted at 143 to a lever 145, fulcrumed midway between its ends on a pin 15 144, (shown in Fig. 1,) which serves as a fulcrum for the shifting-bar lever both at the top and bottom of the weaving mechanism. The result is that when one of the bars 140 is actuated it will through the lever 145 20 actuate the other bar in the opposite direction, so that said shifting-bars move simultaneously in opposite directions. The rear shifting-bar 140 is thus moved by a cam-wheel 146, the rim of which operates between two friction- 25 rollers 147, secured to the rear surface of a strap-plate 148 on the rear surface of the rear shifting-bar 140, as seen in Figs. 7 and 8. The strap 148 moves through a pair of guides 149, secured to the under side of the plate 135 30 of the twister-wheel box.

The cam-wheel 146 is divided practically into two portions or halves, so that during half the revolution thereof it will move the shifting-bars in one direction and during the other half-revolution it will move them in an opposite direction. Said cam-wheel is secured on a shaft 150 (shown in Fig. 5 as mounted at each end on the beam 50) and which is actuated by a gear-wheel 151, that 35 meshes with pinion 152 on the shaft 76, as will be understood from Figs. 3 and 14.

The shifting mechanism will be further understood by an examination of Figs. 7 to 45 13. It will be observed that to the inner surface of each shifting-bar 140 in the left-hand part of the machine, as shown in Figs. 7 and 9, there is secured an inwardly-extending stationary arm 155, as seen in Figs. 10 and 12, with the inner end thereof sharpened, so that each side of the point has the 50 same degree of curvature as the opening 138 in the plates 135 and 136, as shown in Figs. 8 and 9. These rigid shifting-arms 155 are used for shifting the shuttle about the four-inch twister-heads.

For the other twister-heads a different form is used, such as is shown in the right-hand part of Fig. 9 and in Figs. 8, 12, and 13. There a rigid arm 156 is used, the point of 55 which is cut off, it otherwise being like the arm 155, and upon which there is a pivoted shifting-arm 157, that is pointed like the arm 155. It is pivoted on the arm 156 by a pin 158 about midway between its ends, and centrally of its outer end there is a longitudi-

nally-extending slot 159, into which a pin 160 from the upper plate 136 of the twister-box extends, as appears in Fig. 8. Said pin 160 being stationary holds the outer end of the shifting-arm 157 stationary, so as to give its 70 pointed end increased or exaggerated movement or throw, as compared with the rigid arm 155. (Shown in Figs. 10 and 11.) All of the stationary arms 155 and 156 are braced by a longitudinally-extending rod 161, as 75 seen in Figs. 9 to 13.

The function of the shifter-arms 155 and 157 is to move or throw the shuttle from one twister-head to the adjacent twister-head. Assuming the carts to be in the position seen 80 in Fig. 5 and that the twister-head marked A will move in the direction of the arrow, during the further operation of the machine it will carry the shuttle marked B to the right. As this is being done the shifting-bars 140 85 are being moved, the front one going to the left, as indicated by the arrow, so that by the time the twister-head A carries the shuttle B down to the point marked C the shifting-arm marked D will have been moved to the left 90 sufficiently far for its right-hand upper bevelled edge to engage said shuttle B and throw it to the right on the forward side of the twister-head marked E—that is, into the indentation marked F—for by the time the 95 shuttle B gets around to point C the indentation F in the twister-head E will also be at that point and the shifting-arm D will shift the shuttle from the twister-head A to the twister-head E in the indentation F. After 100 the shuttle B thus is thrown into the grasp of the twister-head E it will be revolved two times by said twister-head, thus causing the wire 115 to be coiled or wrapped two times around the strand-wire 66, as shown in Fig. 23. 105

While the two revolutions of the twister-head E are taking place, the cam-wheel 146 is making a half-revolution, and then the cam portion of said wheel acts to move the shifting-bars 140 in the direction the reverse 110 of that which has just been described, so that said shifting-arm D will be thrown from its left-hand position back to its dotted-line position (shown in Fig. 5) in time for its rear left-hand inclined face to engage the shuttle 115 B, which is then in the grasp of the twister-head E, and shift it to the twister-head A and into the same indentation H that it is shown in in Fig. 5, although when the shifting takes place said indentation will be turned 120 to the front side of the figure instead of the upper side, as shown. Then it is carried around by the twister-head A two times and another twist is made. This operation is repeated, so that said shuttle-beam plays 125 back and forth in the twister-heads A and E and always enters the indentations H and F. Likewise the shuttle K will be shifted by the shifting-arm L to and from the twister-heads A and M. The explanation relative to the 130

movement of the shuttles (shown in Fig. 5) in the grasp of the twister-head A also explains fully the movements of the shuttles in each of the other twister-heads shown. It is obvious, therefore, that two shuttles revolve about a tube 96 and therefore a strand-wire at the same time and that two of the diagonal wires 115 are coiled about a strand-wire at the same time and point, excepting the top and bottom wires of the fence fabric or outside wires or strand-wires, as shown in the drawings. Immediately after the two diagonal wires 115 are thus coiled about a strand-wire at the same time and place they are moved away from said strand-wire in opposite directions by the shuttles to the strand-wires on either side. In this way the diagonal mesh is formed. By referring to Fig. 4 it will be observed that on the rod 59 guides

for guiding the lateral strand-wires of the fabric are shown, consisting of an arm or bracket 170, carrying a roller or sheave-pulley 171 thereon that rides in front of and against a wire. Also a wheel 172 rotates on said rod 59 and bears against the inside surface of the strand-wire. There is one on each side that tends to press outward against the strand-wires and maintain the fence fabric at a uniform width and prevent the lateral strand-wires from being drawn inward during the manufacture of the fence. A collar 173 is fastened on the rod 59 at the inner side of the wheel 172 to hold said wheel in the proper position.

The wire fabric is fed through the machine intermittently by the mechanism that drives the reel 71. The reel is mounted on a double shaft, as shown in Figs. 25 and 26, consisting of what may be called the "major" shaft member 180 and a "minor" shaft member 181. The actuating mechanism is mounted on the minor shaft member 181, whereas the reel proper is chiefly mounted on the major portion 180, so that said reel and major portion of the shaft may be removed when desired. The reel consists, in addition to said shaft, of a head 182, mounted loosely on the said shaft 180 and an opposite head 183, that is also mounted loosely on the extreme inner end of the said shaft and extends beyond said shaft member, so as to leave a central recess for the inner end of the minor shaft member 181. As seen in Fig. 26, the adjacent ends of the two shaft members 180 and 181 are square or angular in form and the inner portion of the head 183 is similarly formed, so that the reel may be inserted in place with the head 183 engaging and upon the inner end of the minor shaft member 181. The minor shaft member has a strong stationary bearing-bracket 184, while the outer end of the major shaft member rests upon a bracket 185 and under a strap 186 and is held in place by a removable pin 187, as appears in Fig. 27.

Four longitudinally-extending bars, which may be also numbered 71, engage at their ends loosely said heads 182 and 183 to form the reel. The ends of the wires 66 are fastened to them, as shown for illustration in Fig. 28, preliminary to the weaving of the fabric. The reel is actuated intermittently by a pawl-and-ratchet mechanism. A ratchet-wheel 190 is secured on the shaft and is driven by a set of pawls 191, that extend through a pawl-plate 192, and on their outer ends are held down by springs 193 around bolts 194, that pass through the springs, outer ends of the pawls, and pawl-plate 192, as seen in Fig. 2. These springs hold the pawls in engagement with the ratchet. The ratchet-plate is fastened on a lever 195, that is fulcrumed on the reel-shaft 181, and is actuated by a reciprocating bar 196.

The lever 195 is formed of two parallel bars, as seen in Fig. 16, that extend on each side of the reciprocating bar 196 and between pairs of guiding-lugs 197 loosely, so that said reciprocating bar 196 may be moved up and down with reference to said lever 195 by a screw 198. Said screw 198 passes through a threaded hole in the end of the bar 196 and is mounted on a plate 199 near its lower end, which is secured to the lower portion of the lever 195. Said screw 198 is actuated by a bevel-gear 200, that meshes with a worm 201 on a shaft 202, that is mounted in the lower end of the lever 195, which is driven by a sprocket-wheel 203 and sprocket-chain 204 and a sprocket-wheel 205, that is mounted on the shaft 181.

As the bar 196 is reciprocated it drives the reel in the direction indicated by the arrow intermittently with each movement thereof. As the reel turns it actuates the screw 198, which moves down slowly and gradually the reciprocating bar 196, so that the angular movement of the reel by said reciprocating bar diminishes as the fabric increases in diameter on the reel. The backward movement of the reel is prevented by the pawls 206 on the frame formed of the parts 207 and 208, that are secured to the side of the beam 50.

The bar 196 for actuating the reel is operated forwardly by a bar 210, to which it is pivoted, said bar 210 being pivoted to the post 211, which extends outwardly from the upright 54 of the frame, this part of the mechanism being shown in Figs. 15 to 18. Said bar has a plurality of holes 212, in which a pivot-pin 213 may be located for varying the extent of throw or forward movement of the bar 196. The rearward or return movement of said bar 196 is caused by a spring 214, one end of which is connected with said bar 196 and the other end to the beam 50, as appears in Figs. 1 and 16.

The swinging bar 210 receives its actuating movement from the bar 217, that is pivoted to it by a pin 219, that extends loosely into a

cam groove or guide 220, which is secured to the beams 47 and 50 and has on its end a shoe 221, adapted to be engaged by a pin 222, eccentrically located on a wheel 223, that is mounted on the shaft 76, as seen in Fig. 3. The bar 210 has a number of holes 224 and the bar 217 has a number of holes 225, so that the pivot-pin 218 may be adjusted to suit the extent of movement of the weaving mechanism that may be desired. By referring to Fig. 17 it is seen that as the wheel 223 rotates for one-fourth revolution thereof it will actuate the bars 196, 210, and 217, as appears in Fig. 18.

The extent of the intermittent movements of the reel is further regulated and controlled both by hand and automatically, as will be understood from the following explanation: A bar 230 is suspended from the pin 211 beside the bar 210, and at its lower end it carries a box 231, to which is secured a stop-pin 232, that rests to the rear of the bar 210. Said box 231 and pin 232 may be moved horizontally by a screw 235, mounted in brackets 236, secured to a bar 237, that is movable horizontally in notches in the plates 238, secured on the upright 54, as shown in Fig. 16. Said bar 237 extends over and across the beam 50 and at its rear end is pivoted to a lever 241 between its ends, as seen in Figs. 1 and 27. The lever 241 is fulcrumed at its lower end at 242 to the beam 45 and at its upper end is turned rearwardly at a right angle and has secured to it an arm 239, that bears against the bundle of fabric on the reel, and as said bundle increases it pushes the parts described forward. Such movement of the bar 237 causes the stop-pin 232 to engage and hold relatively farther forward the hanging bar 210, so as to limit the return movement of said bar 210 and reduce the extent of its forward movement by the pin 222 on the wheel 223 in proportion to the increasing size of the bundle of fabric on the reel. The screw 235 is for the purpose of adjusting this automatically-regulated device by hand at any time and for any desired purpose. The screw 235 has a hand-wheel 240. The spring 214 holds the arm 239 against the bundle of fabric on the reel.

It will be thus seen that there are several means herein provided for regulating the extent of movement of the reel in proportion to the size of the bundle of fabric thereon, so that it may have the proper movement to draw the fabric at each step the proper distance and maintain the same taut. After sufficient fabric has been wound upon the reel and it is desired to remove the bundle of fabric the pin 187 is removed and the left-hand end of the reel, as shown in Fig. 24, is disengaged and moved rearwardly and then the whole reel is drawn to the left, so that it will disengage the minor shaft member 181. Then the shaft is removed from the reel that

is in the bundle of wire, and the heads are removed and the slats or bars 71 collapsed and all are then taken out of the bundle.

What I claim as my invention, and desire to secure by Letters Patent, is—

1. In a wire-fabric machine, parallel tubes through each of which a wire may pass, said tubes arranged in series at varying distances apart, shuttles parallel with said tubes and each adapted to carry a wire to be woven with wires passing through said tubes, means on said tubes for revolving said shuttles severally about said tubes, means for shifting each shuttle periodically from one tube to an adjacent tube, gears of the same size on all of said tubes in each series that successively intermesh, there being gears of two series on each tube between adjacent series of tubes, and a single means for driving one tube in all the series, substantially as set forth. 85

2. In a wire-fabric machine, parallel rotary tubes through each of which a wire may pass, a pair of disks secured on each shaft of substantially similar conformation and each provided with a pair of diametric teeth with an indentation beside the teeth, the disks of adjacent tubes overlapping each other, a guide-plate hugging said disks on each side, and a shuttle carrying a wire adapted to be woven with the wires extending through said tubes that projects between said disks beside the teeth thereof, whereby said shuttle will be caused to revolve about said tubes. 95

3. In a wire-fabric machine, parallel rotary tubes each having a wire passing through it, disks on said tubes that overlap each other and have coacting projections and indentations, a plate about said disks and conforming to the curvature thereof, and a shuttle carrying a wire adapted to be woven with the wires extending through said tubes that projects between said plate and disks in the indentations thereof, and means for shifting said shuttle from one disk to the other alternately. 110

4. In a wire-fabric machine, parallel rotary tubes having each a wire through it, a twister-head secured on said tubes and having two parallel disks of similar form each having diametrically-extending teeth with a recess adjacent thereto and said teeth and recesses being in vertical alinement with each other, a pair of plates with openings therethrough to provide a guide within which each of said twister-heads operate, and a shuttle carrying a wire adapted to be woven with wires extending through said tubes that projects between said twister-heads and said plates, whereby the rotation of the tubes will cause the rotation of the shuttles. 120 115 125

5. In a wire-fabric machine, parallel rotary vertical tubes having each a wire passing through it, a twister-head secured to each end of said tubes and having disks with diametrically extending teeth and an indenta- 130 135

tion beside each tooth, a shield-plate hugging each side of said upper and lower twister-heads, a shuttle carrying a wire adapted to be woven with the wires that pass through said tubes that projects between said disks and plate in the indentations of the disk, and loops on said shuttle through which said teeth project, whereby said shuttle will be held in its vertical position and revolved about said tubes.

6. In a wire-fabric machine, parallel rotary tubes through each of which a wire may pass, shuttles adapted to carry other wires to be woven with wires passing through said tubes, means on said tubes for revolving said shuttles about said tubes, a periodically-movable shifter-bar, arms extending rigidly from said shifting-bar, shifting-arms pivoted on said rigid arms that are pointed with a curved bevel on each side of the end, and a stop for limiting the movement of said shifting-arms.

7. In a wire-fabric machine, parallel tubes through each of which a wire may pass, said tubes being in different series, the distance of the tubes apart differing in the different series, shuttles adapted to carry other wires to be woven with the wires passing through said tubes, disks varying in their diameters for revolving the shuttles about said tubes, a shifting-bar mounted at each side of the row of tubes, means for periodically operating said shifting-bars in opposite directions simultaneously, and shifting-arms extending from said shifting-bars in the proximity of said disks, the shifting-arms for the narrow disks being stationary and the shifting-arms for the larger disks being pivoted, said shifting-arms being pointed and having a concave edge at each side of the point, so that each shuttle will be shifted from one disk to the next.

8. In a wire-fabric machine, a frame, means for maintaining the longitudinal strand-wires of the fabric in a vertical position, means for weaving other wires across and with said strand-wires, a transverse rod secured to the frame behind the fabric above the weaving mechanism, a sheave-pulley mounted at each side of the machine on the rod for bearing against the front surface of the lateral strand-wires, and wheels mounted upon said rod that engage the inner surfaces of said strand-wires, substantially as set forth.

9. In a wire-fabric machine, a reel upon which the fabric is wound as it is woven, consisting of a removable shaft, heads loosely mounted on said shaft, and longitudinal bars loosely mounted in said heads.

10. In a fence-fabric machine, a reel having a shaft removably mounted at one end on the framework and a central socket in the other end, and a reel-actuating shaft mounted in the framework upon which the socketed end of the reel may be placed or removed,

whereby the reel is readily mounted and removable.

11. In a fence-fabric machine, a reel upon which the fabric is wound as it is woven, a lever fulcrumed coaxially with the reel, means connected with said lever for actuating the reel in one direction, a reciprocating bar movably engaging said lever, a screw passing through said reciprocating bar, means connected with said lever on which said screw is mounted rotatably, and means for transmitting power from the reel to said screw, whereby the screw will move said bar gradually farther away from the fulcrum of said lever as the operation of the reel proceeds.

12. In a fence-fabric machine, a reel upon which the fabric is wound as it is woven, a lever fulcrumed coaxially with the reel, means connected with said lever for actuating the reel in one direction, a reciprocating bar movably engaging said lever, a screw passing through said reciprocating bar, means on said lever in which said screw has bearing, a bevel-gear on the end of said screw, a worm-wheel mounted in said lever that engages said bevel-gear, a sprocket-wheel connected with said worm-wheel, a sprocket-wheel on the reel-shaft, and a sprocket-chain connecting said sprockets, substantially as set forth.

13. In a fence-fabric machine, a reel for receiving the fabric as it is being woven, a reciprocating bar for intermittently actuating the reel in one direction, a suspended bar to which said reciprocating bar is pivoted, a driving-wheel near said bar, means connected with said swinging bar that is engaged periodically by said wheel for actuating said reciprocating bar in one direction, and adjustable means for limiting the return movement of said swinging bar, whereby the limit of movement of said reel may be regulated.

14. In a fence-fabric machine, a reel for receiving the fabric as it is being woven, a reciprocating bar for intermittently actuating the reel in one direction, a suspended bar to which said reciprocating bar is pivoted, a driving-wheel near said bar, means connected with said swinging bar that is engaged periodically by said wheel for actuating said reciprocating bar in one direction, and adjustable means for limiting the return movement of said swinging bar, whereby the limit of movement of said reel may be regulated.

15. In a fence-fabric machine, a reel for receiving the fabric as it is woven, a reciprocating bar for actuating said reel, a driving-wheel with a pin mounted eccentrically on it, adjustable means engaged by said pin at each revolution of the wheel for moving said reciprocating bar in one direction, and a cam-guide for regulating the position of said means so it will be engaged by the pin on said wheel during various adjustments.

16. In a fence-fabric machine, a reel for receiving the fabric as it is woven, a reciprocating bar for actuating said reel, a driving-wheel with a pin mounted eccentrically on it, adjustable means engaged by said pin at each revolution of the wheel for moving said reciprocating bar in one direction, a cam-guide for regulating the position of said means so it will be engaged by the pin on said wheel during various adjustments, and means actuated by the coil of wire on the

reel for adjusting the position of said moving means.

In witness whereof we have hereunto affixed our signatures in the presence of the 15 witnesses herein named.
